UNITED STATES PATENT OFFICE.

SILAS H. HARDING, JR., NEW CASTLE, NEW HAMPSHIRE.

DESIGN FOR A MARINER'S CLOCK-DIAL.

SPECIFICATION forming part of Design No. 19,255, dated August 6, 1889.

Application filed May 18, 1889. Serial No. 311,341. Term of patent 7 years.

To all whom it may concern:

Be it known that I, SILAS H. HARDING, Jr., a citizen of the United States, residing at New Castle, in the county of Rockingham, State of New Hampshire, have invented and produced a new and original Design for Dials for Mariners' Clocks, of which the following is a specification, reference being had to the accompanying drawing, forming a part thereof, of, in which the figure is a plan view of a dial embodying my improved design.

The leading feature of my design consists in a clock-dial having an annular series of panels surrounding the body of the dial and separated from each other by radial lines and figures disposed in said panels.

This design comprises a central circular panel A and an annular series of panels B, surrounding the central panel.

The panels B, surrounding the central panel A and comprising the annular series, are sep-

arated from each other by radial lines x. Rectangular and triangular figures m are disposed in pairs in said panels. Each of the triangular figures is provided with a dot. Some of the rectangular figures are ornamented with parallel bars, some with crossed bars, the bars being crossed at various angles, and some with blocks.

I claim—

The design for a clock-dial herein shown and described, the same consisting of a circular center panel, an annular series of panels surrounding said circular panel and separated from each other by radial lines, and figures disposed in the panels of the annular series.

SILAS H. HARDING, JR.
